UNITED STATES PATENT OFFICE.

HAROLD D. CHURCH, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,327,147.

Specification of Letters Patent.

Patented Jan. 6, 1920.

Application filed May 11, 1916. Serial No. 96,880.

To all whom it may concern:

Be it known that I, HAROLD D. CHURCH, a citizen of the United States, and resident of Detroit, Wayne county, State of Michigan, have invented certain new and useful Improvements in Hydrocarbon-Motors, of which the following is a specification.

This invention relates to hydrocarbon motors, and particularly to the pistons thereof.

One of the objects of the invention is to provide a piston in the use of which oil will not be drawn into the cylinder from around the skirt portion of the piston.

Another object of the invention is to provide a piston with a scraper part that will scrape oil from the cylinder walls and return it to the crank case.

Another object of the invention is to form a one piece piston so that there will be upper and lower parts separated at the periphery and connected by a suitable web.

Other objects of the invention will appear from the following description taken with the drawings which form a part of this specification and in which:

Figure 1 is a side elevation of a piston embodying this invention;

Fig. 2 is a longitudinal section through the piston shown in Fig. 1; and

Fig. 3 is a section on the line 3-3 of Fig. 2.

In the drawings one embodiment of the invention is shown, but it will be understood that various modifications thereof may be made without departing from the invention, this particular form being merely illustrative, the scope of the invention and the novel features thereof being indicated by the claims.

As shown, a piston formed of a single piece or casting comprises three principal parts, a head portion 10, a skirt portion 11, and a connecting or web portion 12. The head portion has a top 13 and a downwardly extending peripheral flange 14 in which are arranged the usual piston rings 15, any suitable number being used. The upper edge 16 of the skirt portion 11 is slightly separated from the lower edge 17 of the flange

14 thus forming a space 18 between said edges and causing the edge 16 to act as a scraper for the oil on the cylinder walls as the piston moves upwardly.

The web portion 12 is shown as of substantially conical form and connecting the middle part of the top of the head portion with the upper part of the skirt portion. It joins the latter adjacent the upper end. The web portion has several large openings 19 to permit air to pass freely and to also permit the return to the crankcase of the oil scraped off the cylinder walls. Ribs 20 may be used to strengthen the web portion if desired, and two of them may connect the web 65 with piston pin supports or trunnions 21 formed integrally with the upper part of the skirt portion as shown in the drawings.

It will be understood that when a piston is used in the cylinder of a hydrocarbon motor for instance, there is a strong suction past the piston walls during the intake stroke which tends to draw oil from the piston and cylinder walls into the combustion space where it is burned causing carbon deposits and wasting oil. In the use of a piston embodying this invention as shown there will be no suction below the space 18 as whatever leakage there may be past the rings 15 will simply draw air through the 80 openings 19 and the tendency to draw oil from the skirt walls will be obviated.

Also, due to the scraper action of the edge 16 the surplus oil will be carried back into the crankcase through the openings 19.

Having thus described my invention, what I claim and desire to secure by Letters Patent is:

1. A one piece piston comprising upper and lower parts separated at the periphery to form a gap, said piston having a conical web portion connecting its two parts and inclined outwardly toward its lower end and extending directly from adjacent the middle of the upper part to the upper edge 95 of the lower part of the piston.

2. A piston comprising a head portion, a skirt portion slightly separated from the head portion at the periphery and having piston pin supports therein, and a web por- 100

tion connecting the head and skirt portions and extending directly from the upper part of the head portion to adjacent the upper edge of the skirt portion and above said piston pin supports.

3. A piston comprising a head portion, a skirt portion slightly separated from the head portion at the periphery and said skirt

portion having piston pin supports therein, and an integral conical web portion connecting the middle part of said head portion with said skirt portion above said piston pin supports, said web being inclined outwardly toward its lower end. 10

In testimony whereof I affix my signature. 15
HAROLD D. CHURCH.
